TOOTHBRUSH POWER HANDLE OR A SIMILAR ARTICLE

George H. Frost, Mansfield, Ohio, assignor to Westinghouse Electric Corporation, a corporation of Pennsylvania

Filed May 29, 1963, Ser. No. 75,162

Term of patent 14 years

(Cl. D9—2)

FIGURE 1 is a perspective view of a toothbrush power handle or a similar article embodying my new design;

FIGURE 2 is a top plan view of the article shown in FIGURE 1;

FIGURE 3 is a bottom plan view thereof; and

FIGURES 4, 5 and 6 are transverse sectional views, taken along the lines IV—IV, V—V and VI—VI, respectively, looking in the directions indicated by the arrows.

The dominant features of my design are shown in full lines.

I claim:

The ornamental design for a toothbrush power handle or a similar article, substantially as shown and described.
